US00D897304S

(12) **United States Design Patent** (10) **Patent No.:** **US D897,304 S**
Choi et al. (45) **Date of Patent:** **** Sep. 29, 2020**

(54) **MOBILE PHONE**

(71) Applicant: **LG ELECTRONICS INC.**, Seoul (KR)

(72) Inventors: **Hanwool Choi**, Seoul (KR); **Hyoni Kim**, Seoul (KR); **Seungbeom Park**, Seoul (KR); **Hyun Lee**, Seoul (KR); **Jiyoun Cha**, Seoul (KR)

(73) Assignee: **LG ELECTRONICS INC.**, Seoul (KR)

(**) Term: **15 Years**

(21) Appl. No.: **35/505,010**

(22) Filed: **Nov. 30, 2017**

(80) **Hague Agreement Data**

Int. Filing Date: **Nov. 30, 2017**

Int. Reg. No.: **DM/098951**

Int. Reg. Date: **Nov. 30, 2017**

Int. Reg. Pub. Date: **Jun. 1, 2018**

(30) **Foreign Application Priority Data**

May 30, 2017 (KR) 30-2017-0024530
